UNITED STATES PATENT OFFICE.

JACQUES J. KIRKBY, OF CLYMER, NEW YORK, ASSIGNOR TO EARL J. BELLINGER, OF SHERMAN, NEW YORK.

CAN-FILLING MACHINE.

Application filed October 14, 1920. Serial No. 416,921.

To all whom it may concern:

Be it known that I, JACQUES J. KIRKBY, a citizen of the United States, residing at Clymer, in the county of Chautauqua and 5 State of New York, have invented a new and useful Can-Filling Machine, of which the following is a specification.

This invention relates to can filling machines.

10 The present machine is an improvement on the machine described and claimed in an application filed by me March 21, 1919, Serial No. 283,998. This machine, like that of my co-pending application, is particularly adapted to fill tin cans with sweetened condensed milk through a small aperture commonly known as the vent hole of the can. The machine is not limited to use for 15 filling cans with milk, for it may fill any 20 portable receptacle with a fluid having approximately the consistency and viscosity of sweetened condensed milk.

In the machine of the earlier application, 25 much of the driving mechanism was located above the milk reservoir. Since the mechanism had to be kept well lubricated, the oil and grease would occasionally drop down upon the cover of the milk reservoir, creating an unsanitary condition. It is an object of the present invention to construct a 30 can filling machine so that all the driving parts are below the reservoir, or so far to one side of it that no grease or oil whatever can find its way into the reservoir.

35 Another object of this invention is to improve upon the driving mechanism of the earlier construction, eliminating the driving cams and otherwise improving the machine so that the actual power required to 40 drive the same is greatly reduced.

A further object of this invention is to provide a centering device for the empty cans which accurately presents them to the filling nipples.

45 A further object is to provide an improved form of nozzle which allows the escape of air as the can is being filled, whereby the milk will not crust around the can opening.

50 A still further object is to provide means for positively stripping or pulling the filled cans off the filling nipples, thus preventing any catching or jamming of the parts with consequent delay in operation.

An additional object is to provide an improved mechanism for reciprocating the can carriage. 55

Another object is to provide means for guiding the cans after they have been filled, and spacing the same apart from each other 60 as they are moved by the carriage onto a conveyer belt.

A further object is to provide means for adjusting the extent of movement or stroke 65 of the pistons so that exactly the same quantity of milk is forced out of each cylinder into the can below.

Another object is to provide means for preventing choking or too rapid a feed of 70 the empty cans out of the can filling tube.

Another object is to provide an improved mechanism for raising and lowering the cans before and after the feeding operation.

The general objects are to provide a machine which is simple in construction, economical to build and operate, which is absolutely sanitary, and is very rapid in its operation. Other objects will appear from the 75 following specification.

The invention will be best understood 80 from a consideration of the following detailed description taken in connection with the accompanying drawing forming part of this specification, with the understanding, however, that the invention is not confined 85 to any strict conformity with the showing in the drawing, but may be changed and modified so long as such changes and modifications mark no material departure from the salient features of the invention as expressed in the appended claims. 90

In the drawing:—

Fig. 1 is a front elevation of a portion of a machine constructed in accordance with the invention. 95

Fig. 2 is an end elevation of the same, looking from the right hand end of the machine of Fig. 1.

Fig. 3 is a fragmentary elevation with parts in vertical cross section, looking from 100 the same side of the machine as Fig. 2.

Fig. 4 is a plan view, parts broken away and in section, showing the relative location of the mechanism.

Figs. 5 and 6 are detail elevations showing two positions of the means for reciprocating the can carriage. 105

Fig. 7 is a vertical cross sectional view

through the cylinder, piston and reservoir, showing a portion of the can carriage in elevation.

Fig. 8 is a vertical cross section of the improved nozzle.

Fig. 9 is a bottom plan view of the parts shown in Fig. 8.

Fig. 10 is a detail cross sectional view of one of the parts of the nozzle.

10 Figs. 11 and 12 are perspective views of the two cam pieces employed on the disk of Figs. 5 and 6.

Fig. 13 is a detail view showing the mechanism for elevating and lowering the cans.

15 Fig. 14 is a plan view showing the top flange of the I-beam which supports the cans during the filling operation.

Fig. 14^a is an elevation showing the I-beam of Fig. 14 with the knock-off fixtures secured in position.

Fig. 15 is a plan view showing several of the guides and spacers for the cans.

20 Fig. 15^a is an enlarged vertical section illustrating the construction of the spacer member.

Fig. 16 is a top plan view of the can centering device.

Fig. 16^a is a vertical cross sectional view on the line 16^a—16^a of Fig. 16.

30 Fig. 16^b is a bottom plan view of the centering device.

Fig. 17 is an elevation partly in vertical section showing a modified and preferred mechanism for raising and lowering the cans to and from the filling nozzles.

Fig. 18 is a similar view but looking in a direction at right angles.

Fig. 19 is a detail horizontal section of part of the construction shown in Figures 40 17 and 18.

Fig. 20 shows a modified mounting of the plate which prevents choking or too rapid feed of the empty cans from the lower end of the can feeding tube.

45 The present machine has its working parts supported by a frame 20 comprising a number of angle bars bolted or riveted together. This frame includes upright members and horizontal members, the whole 50 being substantially rectangular. At the rear of the frame, as seen in Fig. 2, a platform 21 is provided. An upright shaft 22 is suitably journaled in the frame of the machine substantially midway the shaft's 55 ends and at its upper end a drive pulley 23 is fixed. Near the lower end, the shaft 22 carries a worm 25. That portion of the shaft extending within the main frame of the machine is enclosed by a casing 24, so

60 that no grease from the bearings of the shaft can fall anywhere near the milk reservoir or can. The worm 25 meshes with a worm gear 26, which, in turn, is secured upon the main shaft 27 extending horizontally of the machine. Each end of shaft 27

has a crank disk 28 fixed thereon, and each crank disk is pivotally connected with a connecting rod or pitman 29.

The upper end of each pitman 29 is received between and pivotally secured to a 70 pair of ears 30 formed integrally with a block. Each block is mounted between a pair of channel beams 31 which are secured together so as to form effectively one beam. The pair of beams 31 will hereafter be referred to as the cross-head of the machine, since it is by means of the reciprocation of these united channel beams that the pistons are reciprocated in their cylinders. A guide rod 33 is mounted in upright position at 75 each end of the main frame of the machine and is passed through a plurality of guide blocks 32 mounted between the channel beams 31. From the foregoing description, it should be clear that rotation of the drive 80 shaft 22 will cause reciprocation of the cross-head up and down on the rods 33.

The cross head carries an adjusting sleeve holder 34 by which the adjusting sleeves 35 are received. A piston rod 36 is connected 90 with the lower end of each adjusting sleeve 35 by means of a shear pin 35^a which will break in case anything goes wrong with the feeding of the milk through the nozzles and will thus prevent bursting of the cylinders. 95 The lower end of the piston rod 36 carries a piston (shown in detail in Fig. 7) which enters a cylinder 37 having a plurality of perforations 38 in its side walls arranged in circular series. There are four to six 100 hundred perforations in the cylinder, each of which is smaller than the passageway of the nipple. If the nipple has a passageway of 3/32" these perforations may each have a diameter of 5/64".

The embodiment of the invention illustrated in the accompanying drawings is capable of filling thirty cans with each reciprocation of the cross head. In such case, there will be thirty pistons reciprocating in thirty cylinders similar to cylinder 37. All of said cylinders are enclosed within a reservoir comprising a frame 40 and a reservoir proper 39. It will be understood that for simplicity of description a single 110 cylinder filling nozzle and can is hereafter referred to. Instead of thirty cans being filled in one operation, machines may be 115 built filling a larger or smaller number of cans.

The reservoir has a feed pipe 41 extending therein through which the fresh supplies of the sweetened condensed milk are drawn. The discharge end of the pipe 41 has a valve 42 oscillatable therein, which 125 valve is controlled by a float 43. Obviously, the float 43, when it rises, cuts off the flow of milk into the reservoir and when it sinks permits a fresh supply to come in. At a low point in the reservoir, a drain pipe 44 130

is connected, so that from time to time after the machine has been stopped, the reservoir may be cleaned and the liquid passed out through said pipe. The cylinder 37 below the perforated section thereof is screw threaded, as indicated at 45 (Fig. 3), and passes through the bottom of the reservoir 39. A nut 46 surrounds the screw-threaded section 45 of the cylinder and a gasket 47 is interposed between the nut 46 and the bottom of the reservoir so that a fluid-tight connection is made. A cylinder holder member 48 has screw threads for engagement with the screw threads 45 and is outside of the reservoir 39. Bolts 49 secure the holder member 48 to the top flanges of a pair of channel bars 50. The web of each channel bar 50 is strengthened by a plate 51. The cylinder 37 has a length 20 so as to continue below the bottom of the channel bars 50 and at the lower end is screw threaded as indicated at 52 (Fig. 7). A bottom locking nut 53 engages with threads 52 and also bears against the lower 25 flanges of bars 50. Sockets 54 are provided on the lower edge of nut 53 to render easy the removal of said nut when desired. From the foregoing description, it will be seen that the cylinders 37 are very strongly 30 braced and are absolutely prevented from getting out of alignment in spite of the tremendous pressure to which they are subjected.

A feeding tube 55 for empty cans is supported in an inclined position to the rear of the reservoir, being passed through channel beams 56 and 57, as seen in Fig. 3. The lower end of the tube 55 is secured to a bracket 58, fast to the bottom flange of the adjacent beam 50. Empty cans are delivered to the upper end of each tube 55 with their vent holes uppermost, and such cans are fed one by one from the lower end of each tube to the adjacent nozzle structure, 45 as will be described.

Referring to Fig. 7, it is there seen that the piston rod 36 has a ball-headed stud 59 secured thereto at the lower end, the ball of said stud being held by a cap 60 to a socket member 61. The socket member 61 has an extension which carries the piston 62, lock nuts 64 holding the piston on the extension. Piston rings 63 are provided.

The lower end of cylinder 37 is internally 55 screw threaded for the reception of a cylinder closure member 65. This member holds the improved nozzle structure which forms a part of the present invention (see Figs. 8 and 9). Screw threads 66 are provided on the upper part of the cylinder closure, while the lower part 67 of said closure has sockets 68 for the reception of a wrench whereby the closure may be turned on or off the cylinder end. The upper part 60 of the closure member is chamfered as in-

dicated at 69, and a screw-threaded bore 70 extends axially of the closure. The bottom part of the closure has an annular shoulder 71.

The tubular nozzle member 72 has its 70 lower end formed into a substantially rectangular head with rounded corners, as seen in Fig. 9, and has a reduced screw-threaded section 74 for engagement with the threads 70. The head of this nozzle 75 member fits against the shoulder 71 when it is screwed into place. Teeth 73 project from the lower face of the head 72 and are adapted to space the top of the can from said head so that air escaping from the can 80 during the filling operation may pass out freely.

The nozzle member 72 has an axial screw-threaded bore comprising the sections 75 and 80, the section 75 having a somewhat 85 larger diameter than the section 80. Within the bore 75 a valve seat member 76 is removably secured. This valve seat member has a port 77 centrally thereof, which port is closed by a ball valve 78. The lower 90 part of the valve seat member is suitably hollowed out to provide a chamber in which the ball valve may move. A vent member 79, shown separately in Fig. 10, is held within the screw-threaded bore 80 and has a 95 central passageway 81. Transverse ports 85 are provided above the screw threaded portion of the vent member 79. The upper end of said vent member has a socket 83 and a plurality of slots 84 is arranged circumferentially of the upper end of the vent member. Said upper end is chamfered as shown and the socket 83 is of sufficient diameter to receive a portion of the ball valve 78. The ball valve rests by gravity on the 100 upper end of the vent member, and when so resting, milk may be forced out of the cylinder through the bore 70, the port 77, past the ball valve and through the slots 84 and ports 85, down into the passageway 105 81. A nipple 86 is clamped between the vent member 79 and the head 72, and being removably held, is replaceable when worn out.

A centering device for the cans, shown in 115 Figs. 16, 16^a and 16^b, is clamped upon the cylinder closure 65, as shown in Fig. 7. This centering device may be described as being generally ring-like in form and includes an annular flange 87, a plate 88, and 120 a plurality of arcuate prongs 89, preferably four in number. Such prongs are beveled as indicated at 90, the bevel being on the inside so that the cans are guided thereby. The plate 88 is of irregular form, having 125 one side curved as indicated at 91, the arc of said curve being the same as the arc of the prongs 89. Two other faces of the plate are plane, as indicated at 92, while the fourth face 93 is likewise straight but is 130

tangent to the flange 87; the faces 92 are spaced somewhat from said flange. A set screw 94 provides convenient means by which the centering device is clamped in 5 surrounding relation to the member 65.

The main shaft 27 carries a pair of sprocket wheels 95, (see Fig. 1) each driving a chain 96 meshing with a smaller sprocket wheel 97 on a countershaft 98. 10 Each end of the shaft 98 carries a beveled gear 99 meshing with a similar gear 100. A pair of brackets 104 is provided on each end of the machine for supporting a shaft 101 which is driven by the beveled gear 100. 15 A pulley 102 is keyed on each shaft 101 (see Figs. 1 and 2). A conveyer belt 103 passes over each pulley 102, and near the center of the machine a belt tightening pulley 105 is provided which should be adjustable in the 20 well-known manner so as to take up slack in the belt. The function of the belt 103 is to carry the filled cans out of the machine.

The means for moving the cans from the tubes 55 to the proper position beneath 25 the nozzles will now be described (see Figs. 4, 5, 6, 11 and 12). Upon the main shaft 27, a disk 106 is made fast. This disk carries a pair of cam pieces 109 and 111 on its opposite faces. It therefore may be called 30 a cam disk. A bifurcated arm 107 straddles the cam disk 106 and each furcation has an elongated slot 108 straddling the shaft 27. The cam piece 109 projects outwardly from the face of the disk 106 to which it is secured, and during the rotation of said disk, 35 this cam piece is brought into engagement with a roller 110 provided on the extremity of one of the furcations. The action of the engagement of the cam piece with this 40 roller will be to move the arm 107 downwardly, as shown in Fig. 6, the arm being guided in such movement by its straddling the shaft 27. The other cam piece 111 projects from the opposite face of the disk and 45 engages with a roller 110^a provided on the adjacent furcation. The roller 110^a, as indicated, is at the upper end of the corresponding slot 108, while the roller 110 is at the lower end of the respective slot. The 50 effect of the engagement of cam piece 111 with the roller 110^a is illustrated in Fig. 5, where it is seen that the arm 107 is moved upwardly.

The upper end of arm 107 is pivotally 55 connected to a crank arm 112, in turn secured to a countershaft 113. Upon the countershaft 113 a plurality of segmental gears 114 is secured, such gears having teeth 115 meshing with racks 116. By the 60 mechanism which has just been described, it will be clear that rotation of the main shaft 27 effects reciprocation of the rack 116. Such racks are secured to a horizontally reciprocable carriage on the under- 65 side thereof. The carriage comprises a

lower plate 117 and an upper plate 118, these two plates being duplicates but spaced from each other by sleeves or the like a sufficient distance so that the depth of this carriage approaches the height of the cans. The two 70 plates 117 and 118 have arcuate slots 119 in registering or matching relation, each pair of said slots engaging with a can so that the carriage may push a plurality of cans horizontally into a position beneath the 75 filling nipples. The ends of the carriage have wheels 120 mounted thereon, which wheels run over a rail 121 fixed upon the frame. See Fig. 3. Each rail 121 is cut away near its inner end as indicated at 125 to permit raising of the can-lifting beam and is supported by a channel member 122. Snub posts 123 are provided at convenient points upon the upper plate of the carriage, such snub posts having horizontal bores for 80 receiving guide rods 124, which are in turn made fast to the main frame 20. Thus the carriage, as it reciprocates over the rails 121, is guided and in part supported. The cans moving downwardly through the tubes 55 85 rest upon the upper plate of the carriage until it has moved to a position to one side of the mouth of the tube. Then the lowermost can from each tube falls below and is received within the adjacent slot 119, whereby it will be moved forward by the carriage in a straight line. A spring or gravity actuated plate 130 is supported at the lower 90 end of each tube 55 and is lifted upwardly by the moving of the carriage under the nozzles and swings downwardly into a substantially vertical position when the carriage moves in opposite direction. This plate 95 prevents the cans from choking at the mouth of the delivery tubes 55 and positively directs each can into the niche or seat provided by the aligned slots 119. As shown in Fig. 20, a plate 160 may be provided similar to plate 130 but pivoted upon the channel beam 50 instead of upon the can feeding 100 tube 55.

Extending longitudinally of the machine 105 is a channel bar 126, the upper face of which carries a plurality of can spacers and guiding members 128. As seen in Figs. 15 and 15^a, these spacers taper slightly at each end as indicated at 129 and are undercut, as shown at 129^a. This undercutting is for the purpose of accommodating the bead or crimp at the bottom of each can. Another 115 channel bar 127 provides a support for the belt 103 and extends adjacent the channel bar 126 but slightly below the latter, so that the top of the belt is about on a level with the upper face of channel bar 126. A table 120 is provided by a relatively wide channel bar 147, such table being on a level with the top of belt 103. As seen in Fig. 2, one of the cross angle bars forming a part of the main frame 20 is cut away as indicated 125 130

at 104^a, so that the cans carried by the conveyer belt 103 may pass out of one end of the machine.

The means for lifting the empty cans to the filling nozzles, holding them during the filling operation, and moving them from the nozzles after they have been filled will now be described. The main shaft 27 carries a cam disk 131 (see Fig. 13). This cam disk 10 has a slot cut therein, said slot including a radially-extending wall 132, an arcuate wall 133 concentric to the shaft 27, and a wall 134 at right angles to the wall 132 and spaced from the latter by the arcuate wall 133. An arm 135 has a bent section 136 forming an acute angle with the main part of said arm and bifurcated at its extremity and supports a cam roller 137. This roller runs over the periphery of the cam disk 131 20 and enters the slot of the cam disk to cause oscillation of the arm 135 during each revolution of the cam disk. The other end of arm 135 is secured upon a countershaft 138, which, in turn, as seen in Fig. 4, has secured to it, at intervals, lifting arms 139. An I-beam 140 has its lower flange engaged by these lifting arms and this beam is guided so that oscillation of arm 135 causes vertical reciprocation of said beam.

As seen in Figs. 14 and 14^a, the I-beam 140 is provided with a plurality of bores 143 extending from its upper flange 141 part way into the web. The axes of the bores 142 are slightly offset from the longitudinal center of the beam 140, as seen in Fig. 14. The I-beam 140, which may be termed a can-lifting beam, is also provided with a plurality of threaded bores 143 which are likewise offset but on the opposite side 40 of the beam. Into each screw-threaded bore a T-shaped fixture hereinafter termed the "knock-off" fixture is secured. Each knock-off fixture 145 has its upper end provided with a pair of arms 146 extending at right angles to the shank of the fixture in opposite directions. The spacing of these fixtures is such that a can is receivable between adjacent pairs of the fixtures with the arms 146 overlying the top of the can. Because of the fact that the bores 143 are offset, the knock-off fixtures are likewise offset with respect to the longitudinal center of the beam and they are spaced closer together than a distance equal to the diameter of the cans so that their arms 146 55 nearly meet. The offset bores 142 are provided so that in case the operator who feeds empty cans into the tubes 55 fails to supply any one of these tubes, in which event upon the downward stroke of the corresponding piston, the milk would be forced out of the cylinder, the milk will pass out through the corresponding bore 142 to a catch pan below. The knock-off fixtures 60 positively strip the cans off the nipples and

prevent any jamming and consequent stopping of operations.

The milk reservoir has a cover 148 (see Figs. 1 and 2), with handles 149 at convenient intervals. This cover keeps all 70 dust and all foreign matter out of the milk to be placed in the cans. A sight glass 150, seen in Fig. 1, is provided at the front of the machine so that the operator can determine the level of the milk in the reservoir. 75

The machine is entirely automatic. The empty cans descend through the tubes 55; are prevented from overturning by the plate 130; are engaged by the reciprocating carriage, then moved to the proper position upon the top flange of beam 140; are lifted by said beam; are centered by the pronged centering device; are filled by a single stroke of the cross head; are positively stripped from the nipples by the knock-off fixture; are moved by the next reciprocation of the carriage onto beam 126 where they are maintained in spaced relation by the spacer bars 128; and finally are pushed onto the belt 103 by the succeeding row of cans and are 80 carried out of the machine for the sealing operation. 85

The cylinder perforations 38 strain the milk and prevent foreign matter from being forced into the cans along with the milk; 95 this is a feature which is described and claimed in my co-pending application referred to. The faces 92 of the can centering devices abut each other and positively prevent any turning of each device relative to 100 the nozzle on which it is mounted. The set screws 94 prevent the centering devices from falling off while permitting ready detaching. The face 93 is tangent to the flange 87 to make room for the lifting of plates 105 130 or 160 (Figs. 7 and 20).

The construction of Figs. 17, 18 and 19 is somewhat of an improvement upon the can lifting means shown in the other figures of the drawing, simpler and more direct, and for this reason it may be regarded as my preferred construction. The counter-shaft 138 with the lift arms 139 are done away with and instead a direct acting mechanism of extreme simplicity but of great strength 115 is employed. In Fig. 17, the main shaft 27 is shown as provided with a cam 153 having a slot 154 extending inwardly from its periphery. A block 152 is secured to the main frame of the machine and a pair of thrust columns 151 extend vertically from the block 152 and parallel to each other. Between the thrust columns 151 a bracket 155 is secured to the frame; and a plunger 156 is slidable in the bracket. (Figs. 18 and 19). The plunger 156 has a key-way 159 adapted to receive a key provided on the bracket, whereby the plunger will not turn about its longitudinal axis. The lower end 120 of the plunger has a roller 158 designed to 125 130

ride upon the periphery of the cam 153 and into and out of its slot 154. An adjusting screw 157 is carried on the upper end of plunger 156; and this adjusting screw has an enlarged flat-topped head adapted to engage with the lower edge of the can lifting I-beam 140. Thus driving of the main shaft 27 effects the desired reciprocation of the can lifting beam and at the same time 10 the construction is considerably simplified.

What is claimed is:—

1. In a can filling machine, a plurality of cylinders, a piston reciprocable in each cylinder, a closure for the lower end of each cylinder, a nozzle mounted in each closure, a can centering device mounted upon each closure, means to prevent each can centering device from dropping off the closure, each can centering device being so shaped as to 15 cooperate with the devices on either side thereof to prevent turning of the same, each centering device having a plurality of prongs which are curved to engage the side walls of the cans and beveled to center the 20 cans.

2. In a can filling machine, a plurality of centering devices each comprising a plate, an annular flange provided on said plate, means mounted on the flange whereby the centering device may be held upon a nozzle structure in surrounding relation thereto, transversely curved prongs depending from the side of the plate opposite to that from which the flange extends, said plate having 30 a central opening or bore for the reception of the nozzle structure upon which the device is mounted, the side faces of said plate being straight and in contact so that no one of these devices may be turned relative to the 35 nozzle structure upon which it is mounted.

3. In a can filling machine, a can support, means for reciprocating said support in a vertical direction, nozzles toward and from which the cans are moved, a nipple forming a part of each nozzle, and means 45 mounted on said support for positively stripping the cans off said nipples after the cans are full and when the support is lowered, said means comprising fixtures of 50 T shape including a straight upright shank and a pair of arms each lying in the same line but extending in opposite directions at the upper extremity of said shank.

4. In a can filling machine, a can support, a nozzle toward and from which the cans are moved, a nipple forming a part of each nozzle, and means mounted on said support for positively stripping the cans off said nipples after the cans are full and 55 when the support is lowered, said means comprising fixtures of T shape each including a straight upright shank and a pair of arms each lying in the same line but extending in opposite directions at the 60 upper extremity of said shank, the extremi-

ties of arms of adjacent fixtures being spaced from each other and said arms being spaced from the top of the support a distance somewhat exceeding the height of the cans.

70

5. In a can filling machine, a cylinder, a cylinder closure for the lower end thereof, a nozzle structure removably mounted within said closure, the closure in turn being removably mounted upon the cylinder, said nozzle structure having a pair of opposed valve seats, a valve movable in the space between said seats and closing said cylinder when in raised position, and a nipple projecting from the lower end of the nozzle structure and removable therefrom.

75

6. In a can filling machine, a nozzle structure including a vent member, said vent member being removably mounted within the nozzle structure and having a central longitudinal bore, transversely extending ports provided near the upper end of said vent member, a cylindrical socket provided at the upper end of said member, and a plurality of slots provided in the side wall 80 of said socket, said socket being adapted to partially receive a ball valve.

85

7. In a can filling machine, means for feeding a supply of empty cans to the machine, and means for moving said cans transversely of the machine and in a substantially horizontal path, said means comprising a reciprocating carriage, said carriage including spaced upper and lower plates, each plate having a niche for seating a can, a snub post extending above the top plate, and a horizontal guide rod passing through the snub post for partially supporting as well as guiding the carriage during its movements.

100

8. In a can filling machine, a reciprocating carriage, means for actuating said carriage including a rack mounted on the bottom of the carriage, a segmental gear meshing with said rack, a shaft to which said gear is fixed, a crank arm connected to said shaft, a bifurcated arm pivotally attached to the outer end of the crank arm, a main drive shaft, a cam disk mounted on said main shaft, said bifurcated arm straddling said cam disk, the cam disk effecting movement of the bifurcated arm to cause oscillation of the shaft on which the segmental disk is mounted.

110

9. In a can filling machine, a reciprocating carriage, means for actuating said carriage including a rack mounted on the bottom of the carriage, a segmental gear meshing with said rack, a shaft to which said gear is fixed, a crank arm connected to said shaft, a bifurcated arm pivotally attached to the outer end of the crank arm, a main drive shaft, a cam disk mounted on said main shaft, said bifurcated arm straddling said cam disk, each furcation of

- the arm having a slot receiving the driving shaft, a roller on the lower extremity of the slot of one furcation, a similar roller at the upper extremity of the slot of the other furcation, cam means on the corresponding faces of the cam disk for engaging with said rollers, the cam disk effecting movement of the bifurcated arm and to cause oscillation of the shaft on which the segmental disk is mounted.
10. In a can filling machine, means for raising and lowering the cans to move the same toward and from the filling means, said raising and lowering means including a can support, said can support comprising a flanged beam, the upper flange having a plurality of bores therein extending into the web of the beam and slightly offset relative to the beam.
15. In a can filling machine, means for raising and lowering the cans to move the same toward and from the filling means, including a can support, said can support comprising a flanged beam, the upper flange having a plurality of bores therein extending into the web of the beam and slightly offset relative to the beam, and a second series of bores interposed between the first-mentioned bores, said second bores being screw threaded and relatively small in diameter, and fixtures mounted in the screw-threaded bores and upstanding from the top flange of the beam for positively forcing the cans downwardly at the same time the beam is lowered.
20. In a can filling machine, means for raising and lowering the cans to move the same toward and from the filling means, including a can support, said can support comprising a flanged beam, the upper flange having a plurality of bores therein extending into the web of the beam and slightly offset relative to the beam, and a second series of bores interposed between the first-mentioned bores, said second bores being screw threaded and relatively small in diameter, and fixtures mounted in the screw-threaded bores and upstanding from the top flange of the beam for positively forcing the cans downwardly at the same time the beam is lowered.
25. In a can filling machine, means for raising and lowering the cans to move the same toward and from the filling means, including a can support, said can support comprising a flanged beam, the upper flange having a plurality of bores therein extending into the web of the beam and slightly offset relative to the beam, and a second series of bores interposed between the first-mentioned bores, said second bores being screw threaded and relatively small in diameter, and fixtures mounted in the screw-threaded bores and upstanding from the top flange of the beam for positively forcing the cans downwardly at the same time the beam is lowered.
30. In a can filling machine, means for raising and lowering the cans to move the same toward and from the filling means, including a can support, said can support comprising a flanged beam, the upper flange having a plurality of bores therein extending into the web of the beam and slightly offset relative to the beam, and a second series of bores interposed between the first-mentioned bores, said second bores being screw threaded and relatively small in diameter, and fixtures mounted in the screw-threaded bores and upstanding from the top flange of the beam for positively forcing the cans downwardly at the same time the beam is lowered.
35. In a can filling machine, means for raising and lowering the cans to move the same toward and from the filling means, including a can support, said can support comprising a flanged beam, the upper flange having a plurality of bores therein extending into the web of the beam and slightly offset relative to the beam, and a second series of bores interposed between the first-mentioned bores, said second bores being screw threaded and relatively small in diameter, and fixtures mounted in the screw-threaded bores and upstanding from the top flange of the beam for positively forcing the cans downwardly at the same time the beam is lowered.
40. In a can filling machine, means for raising and lowering the cans before and after the filling operation comprising a beam, an arm engageable with the under side of said beam, a shaft upon which said arm is mounted, the upper side of said beam supporting the cans, and means for oscillating said shaft including an arm mounted on the shaft, said arm having a bent portion at its outer end, a roller at the extremity of the bent portion, said bent portion making an acute angle with the main part of said arm, a main drive shaft, a disk secured upon said shaft to rotate therewith, a slot
- in said disk having a radially extending wall, an arcuate wall concentric with the drive shaft, and a wall at right angles to the radial wall, the roller on said arm riding over the periphery of the disk and into 55 and out of said slot.
13. In a can filling machine, means for feeding empty cans into a machine, including a reciprocatory can pushing carriage, and a tube down which the cans may slide 60 into a position to be moved by said carriage, a plate mounted to swing at the lower end of the tube and normally seeking a vertical position, whereby cans emerging from the tube are prevented by the plate from overturning and whereby the carriage may move the cans while upright into filling position.
14. In a can filling machine, means for feeding empty cans to the machine, means for preventing overturning of the cans as 70 they issue from the feeding means, means for pushing the upright cans transversely of the machine, means for lifting the cans in juxtaposition to the filling means, means for forcing the cans downwardly after the 75 filling operation, means for guiding and spacing the cans apart after they have been filled, and means for conveying the filled cans out of the machine.
15. In a can filling machine, means for 80 raising and lowering the cans to move the same toward and from the filling means, including a can support, said can support comprising a flanged beam, the upper flange having a 85 plurality of bores therein being screw threaded and relatively small in diameter and offset relative to the beam web, and fixtures mounted in the screw-threaded bores and upstanding from the top flange 90 of the beam for positively forcing the cans downwardly at the same time the beam is lowered, said fixtures being offset whereby when the cans are raised the fixtures do not interfere with the can filling operation. 95
- In testimony that I claim the foregoing as my own, I have hereto affixed my signature.

JACQUES J. KIRKBY.
